UNITED STATES PATENT OFFICE.

WILLARD J. BELL, OF NEWAYGO, MICHIGAN.

DISINTEGRATING AND MIXING PROCESS AND MECHANISM FOR CARRYING OUT
THE SAME.

Application filed February 9, 1923. Serial No. 617,990.

To all whom it may concern:

Be it known that I, WILLARD J. BELL, a citizen of the United States, residing at Newaygo, in the county of Newaygo and

5 State of Michigan, have invented new and useful Improvements in Disintegrating and Mixing Processes and Mechanisms for Carrying Out the Same, of which the following is a specification.

10 The present invention relates to disintegrating and mixing processes, and mechanisms for carrying out the same; and its object is to provide a process whereby the flocculent particles in a mass of molding sand may be disintegrated and then intimately and uniformly mixed with other particles thereof more effectively than hitherto; and further, to provide improved mechanisms whereby said process may be 15 practiced; and further, to provide such mechanisms in combination with means whereby additional steps in properly conditioning molding sand may be very effectively carried out.

20 My said process and mechanisms are particularly described in the body of this specification, the accompanying drawings illustrating a preferable embodiment of the mechanical features of my invention.

25 In said drawings:

Figure 1 is a side view of a machine for disintegrating flocculent particles in a mass of molding sand and for then intimately and uniformly mixing the same with other 30 particles of the mass, and for further properly conditioning such sand, the near side of said machine being partly broken away to show interior parts which are sectioned on line 1-1 of Figure 2;

35 Figure 2 is a front view of the same, the feeding chute and belt conveyor being omitted in this view, certain parts being broken away, and other parts being sectioned on line 2-2 of Figure 1;

40 Figure 3 is a top plan view of a vibratile screen partly broken away to show vibrating means;

45 Figure 4 is a side view of said means and an edgewise view of the screen;

50 Figure 5 is a sectional view of disintegrat-

ing and mixing elements of the machine taken on line 5-5 of Figure 1;

Figure 6 is a front view of an electromagnet and adjacent parts;

55 Figure 7 is a sectional view of the same taken on line 7-7 of Figure 6; and

Figure 8 is a modified construction of certain parts shown in the same section as are corresponding parts in Figure 1.

Molding sand is ordinarily a mixture of 60 different kinds of sand, one of which containing a considerable amount of fine vegetable fibre contributes to make the mass in which it is mixed "fluffy," i. e. of such nature that the gases from the molten metal 65 quickly and uniformly escape through the sand so that the casting may conform to the pattern without distortion. The other kinds of sand in the mixture, being wholly granular, are easily screened to desired size; 70 but in the kind which contains the fibre the sand particles adhere more or less to the vegetable fibre, thus becoming flocculent when worked or screened, i. e. forming balls sometimes as large as one-half inch in diameter. Therefore in the process of screening sand containing this fibre, such balls do 75 not pass through the screen, but are eliminated by the screening process, so that the resulting screened and properly sized sand necessarily lacks the desirable qualities 80 which the vegetable fibre imparts. It has thus been difficult hitherto to screen the sand to proper size and also uniformly and intimately mix the said fibre throughout the 85 granular sand in the mass; and much of the kind of sand which contains said fibre (being the most expensive kind) has been lost and wasted in attempting such mixing and screening processes.

90 In my process, I subject the mass of molding sand, including the fibre-containing kind, to the action of rigid or comparatively rigid disintegrating and mixing means operating on the mass at one side thereof, and to 95 the action of flexible or comparatively flexible disintegrating and mixing means operating on the mass at the opposite side thereof. The combined action of these two means effects the breaking up or disinte- 100

grating of the flocculent portions containing the fibre; the brushing out or separating of the fibre by the more flexible means; the picking or carding of the fibre from the more flexible means by the more rigid means; and finally, the intimately mixing together of all the particles in the mass and the uniformly distributing of the fibre throughout the entire mass.

10 By the machine illustrated in the drawings, this my process, and further steps in properly conditioning the sand for molding, may be carried out. In this machine, the mass of sand containing the flocculent particles aforesaid is delivered between cooperating elements, one of which, the rotatable element 1 has comparatively rigid disintegrating projections, the stiff metallic fingers 2, and the other of which, the concave-faced element 3 has comparatively flexible disintegrating projections, the flexible steel bristles 4 forming a steel brush; the projections 2 extending toward the projections 4. The element 3 is mounted 25 at 5 swingably toward and away from element 1 and is pressed toward it by the spring 6 whose tension is adjustable by the screw 7 having the nut 20, the element 3 being held in such position that its upper edge is 30 further from the axis of the element 1 than is its lower edge, as shown in Figure 1.

The element 1, being rotated—at, say 400 revolutions per minute—by suitable power applied as by the motor 8 whose pulley 9 and the pulley 10 on the shaft of said element carry the belt 21, effects in combination with the element 3 the disintegrating and mixing of the mass of sand described above as my process.

40 Additional means for further conditioning molding sand are shown in the drawings. Sand already used for molding frequently contains particles of metal. Such sand disintegrated and mixed by the elements 1 and 3 falls through the screen 11 beneath them and into a suitable box 12, but the metallic particles remaining on the screen slide off the same, over the inclined ledge 13 and into the field of the electromagnet 14, and when the magnet is deenergized fall into the box 15, the screen being vibrated by the percussing action of the rotatable member 16 having cam portions 17 bearing on the bar 18 on the under side of the screen, said member being driven as by its pulley 19 which with the pulley 23 on the shaft of element 1 carries the belt 24.

A chute 25 extending upwardly from its mouth or scoop portion 26 near the floor 27 contains a bucket-carrying belt conveyor 28 extending upwardly in the chute and adapted to discharge from its upper portion molding sand scooped from the floor by the travel of the machine on its wheels 29, into 45 the field of operation of the elements 1 and

3. This belt conveyor may be driven by the belt 30 carried by pulley 31 on its shaft and by the pulley 32 on the shaft of element 1.

In Figure 8 a modified construction of the mounting of the element 3 is shown. In this view said element is swingably mounted adjacent its upper edge at 51 on a threaded bolt 35 having nuts 36, 37 on opposite sides of the supporting frame 38, so that this element's axis of swinging may be adjusted to desired fixed positions nearer to or further from the rotatable element 1. In this construction the screw 71 whose nut 201 adjusts the tension of the spring 61 is pivotally connected at 39 to element 3 adjacent its lower edge. It will be seen that by this construction the pressure of element 3 toward the moving mass of sand may be regulated, in addition to fixedly adjusting the feeding opening (between element 1 85 and the upper edge of element 3) wider or narrower.

I claim:

1. The process of disintegrating the flocculent particles in a mass of molding sand and intimately mixing the same with other particles in the mass, which consists in subjecting the mass to rigidly disintegrating and mixing action at one side of the mass and to cooperating yieldingly disintegrating and mixing action at the opposite side of the mass.

2. The process of disintegrating the flocculent particles in a mass of molding sand and intimately mixing the same with other particles in the mass, which consists in subjecting the mass to rigidly disintegrating and mixing action at one side of the mass and to cooperating yieldingly disintegrating and mixing action at the opposite side of the mass, said actions operating in inter-relatively different directions.

3. The process of disintegrating the flocculent particles in a mass of molding sand and intimately mixing the same with other particles in the mass, which consists in subjecting the mass to comparatively-rigidly disintegrating and mixing action at one side of the mass and cooperating comparatively-yieldingly disintegrating and mixing action at the opposite side of the mass.

4. In a machine of the character described; a rotatable element having disintegrating projections; an element having disintegrating projections cooperating with and extending toward those of the first-mentioned element, and being mounted swingably toward and away from said first-mentioned element, the projections of one of said elements being comparatively rigid and those of the other element being comparatively flexible; means for adjustably pressing said swingably mounted element toward the rotatable element; means for ad-

justing to fixed positions the swingably mounted element's axis of swinging.

5. The process of disintegrating the flocculent particles in a mass of molding sand and intimately mixing the same with other particles in the mass, which consists in subjecting the moving mass to rigidly disintegrating and mixing action at one side of the mass and to cooperating yieldingly disintegrating and mixing action at the opposite side of the mass.

6. The process of disintegrating the flocculent particles in a mass of molding sand and intimately mixing the same with other particles in the mass, which consists in subjecting the moving mass to rigidly disintegrating and mixing action at one side of the mass and to cooperating yieldingly disinte-

grating and mixing action at the opposite side of the mass, said actions operating in 20 interrelatively different directions.

7. The process of disintegrating the flocculent particles in a mass of molding sand and intimately mixing the same with other particles in the mass, which consists in subjecting the moving mass to comparatively-rigidly disintegrating and mixing action at one side of the mass and cooperating comparatively-yieldingly disintegrating and mixing action at the opposite side of the 30 mass.

In testimony whereof I have hereunto set my hand at Grand Rapids, Michigan, this 1st day of February, 1923.

WILLARD J. BELL.
